HYPODERMIC SYRINGE

Ralph Lee Huber, Seattle, Wash.; Jennie Huber, administratrix of said Ralph Lee Huber, deceased

Application February 8, 1951, Serial No. 210,047

9 Claims. (Cl. 128—218)

1

This invention relates to hypodermic syringes and it has reference more particularly to improvements in syringes that are operable to eject a liquid medicament directly from an ampoule through a hypodermic needle; the present device being a syringe of that type designated as a "one shot" syringe, in that it is the intent that it shall be used only once and thrown away or discarded after use. Furthermore, the present invention relates to syringes of that type employed for the hypodermic injection of a medicament from a containing ampoule of cylindrical form and closed at its ends by means of rubber stopples, one of which is caused to be pierced by the inner end of the needle and the other is operable as a piston whereby the medicine is then forcibly discharged through the needle.

The principal objects of the present invention are to provide a syringe of the character or type above mentioned, having improved details of construction that make possible, upon the insertion of the needle, an easy and satisfactory aspiration to determine the correctness of the insertion before causing its inner end to pierce the stopple of the ampoule; to provide a construction whereby an external pressure will be built up about the ampoule during the forced ejection of medicament therefrom to counteract increased internal pressure as an insurance against cracking or exploding the ampoule; to provide means for the accurate centering and aligning of the ampoule in the barrel of the syringe; to provide for the use of an ampoule that can be completely sterilized and then sealed in and maintained in a sterile condition in the syringe barrel until after use of the medicament; to provide a syringe that can be sterilized and then sealed and maintained in sterile condition until time of use.

It is also an object of this invention to provide a "one shot" syringe that can be manufactured at a lesser cost than present day devices used for a like purpose and which has various advantages in use.

Still further objects of my invention reside in the details of construction of the various parts embodied therein; in their combination and mode of use as will hereinafter be fully described.

In accomplishing these and other objects of my invention, I have provided the improved details of construction, the preferred forms of which are illustrated in the accompanying drawings, wherein—

Fig. 1 is a side view of a hypodermic syringe embodying the features of the present invention therein.

2

Fig. 2 is a somewhat enlarged, longitudinal section of the syringe, showing the ampoule as sealed therein, and before the needle has been caused to pierce the outer end stopple of the ampoule.

Fig. 3 is a central, longitudinal sectional view of the syringe showing the relationship of parts near the end of an injection operation.

Fig. 4 is a perspective view of the main parts 10 of the syringe and the ampoule, shown in a separated relationship.

Fig. 5 is an enlarged, cross-sectional view taken on the line 5—5 in Fig. 3.

Fig. 6 is a sectional detail showing the encasing of the needle in a removable sleeve.

Fig. 7 is a sectional detail showing the slight flaring of the end of the plunger sleeve.

Referring more in detail to the drawings—

The present syringe comprises two principal parts, one of which is referred to as the "barrel" and is designated in its entirety by reference numeral 10, and the other being referred to as the "plunger" and is designated in its entirety by reference character 12.

25 The barrel 10 comprises a uniformly cylindrical body portion 10', closed at that end which will be herein designated as its outer end, by an integrally cast wall 11. The opposite end of the barrel is open, and is there formed with an integral, encircling finger flange 13.

The needle employed with this syringe comprises the usual tubular cannula 15 that is mounted in the end wall 11 of the barrel, and extends therefrom coaxial of the barrel. The mounting end portion of the needle is sealed within a hub 16, cast on the end wall. To insure against possible endwise slippage of the needle under inserting pressure, it is slightly bent, as at 17, in that portion contained within the hub 16. The inner end of the needle extends a suitable distance, for example about one-fourth inch within the barrel and is beveled to a sharpened point as designated at 18. The outer end of the needle also is sharpened or pointed as designated at 19, for easy insertion in the flesh of the patient.

40 The plunger 12 comprises a uniformly cylindrical body 12' having an outside diameter that is substantially equal to the inside diameter of the barrel body 10', so that it can be telescopically fitted therein for reciprocal action. At its outer end the cylindrical body 12' is integrally cast with a thumb piece 25 that closes that end of the body and whereby the plunger may be manipulated. Contained coaxially within the cylindrical body 12' is a stem or push rod 26.

This has its outer end integrally cast with the thumb piece 25 as clearly shown in Fig. 2, and extends therefrom substantially the full length of the body 12', preferably terminating slightly within it, as shown, but not necessarily so. Also, as shown best in Fig. 2 there is substantial clearance between the push rod and tubular body 12', providing the annular clearance space designated at 28 in Fig. 2.

A special feature of the construction of the body 12' resides in the beveling and slight flaring of the inner end portion of the body, as at 29, from the outer periphery inwardly to reduce this end to a thin, flexible edge, that will press tightly against the inside surface of the barrel to form an air tight joint. The purpose of this beveled formation will presently be better understood. Fig. 7 illustrates the flaring of the end of plunger 12.

The ampoule used with this syringe and in which the medicament is contained is designated in its entirety in Fig. 4 by reference character 35. It comprises a uniformly cylindrical glass tube 35x, having a length that is approximately equal to that of the barrel 10. It is closed at its outer end by a rubber stopple 36, and at its other end it is fitted with a stopple 37 set somewhat within the end portion. The medicament is indicated in Fig. 2, at 38. It is observed that the stopple 36 has an encircling, outer end flange 39 abutted against the end of the tube to limit its inward disposition thereinto, and the stopple has an inner end recess extended to near the closed outer end of the stopple.

The stopple 37 is of plug form and is fitted as a piston for movement in the tube toward the closed, opposite end under pressure as applied by the push rod 26 of the plunger as presently explained.

The exterior diameter of the ampoule is slightly less than the interior diameter of the cylindrical body 12' of the plunger, thus providing a slight clearance between them when the parts are assembled as in Figs. 2 and 3. When the ampoule is applied to the barrel 10, and the plunger assembled with the barrel for packaging, the parts assume the relationship shown in Fig. 2. The push rod 26 enters the outer end of the ampoule with slight clearance and engages the stopple 37. The beveled end of sleeve 12' enters the open end of the barrel in a close air tight fit. It is to be noted that the inside diameter of the barrel 10' is decreased for a short distance next to the closed end, to provide a cylindrical portion 40. The inner end portion of the ampoule, is received within this portion 40 of reduced diameter to center the ampoule and stopple 36 relative to the inner end portion of the needle. The portion of reduced diameter, merges into the part of larger diameter in an inclined or beveled annular surface 41 in order that the ampoule will be easily received in the part 40.

It is also to be observed, more particularly by reference to Fig. 5, that the cylindrical sleeve 12' of the plunger is formed interiorly with three or more equally angularly spaced longitudinal ribs 45 designed to receive the outer end portion of the ampoule therein and to lightly grip the outer surface of the ampoule when the parts are assembled together as in Fig. 2.

It is the intent that prior to the assembling of the parts as in Fig. 2, all shall be properly sterilized. Then the filled ampoule is placed in the barrel, and the plunger applied thereto as

5 shown in Fig. 2. A suitable sealing jelly may be applied about the plunger to seal the joint where it enters the barrel, and then the unit can be placed within a sterile container of plastic, or other suitable material and the bag or container sealed, or alternatively, a sterile cap as at 43 can be applied over the needle, as in Fig. 6, and sealed over the hub 16.

6 To use the syringe, the enclosing bag, container or cap is removed and the needle prepared for insertion; this being effected by gripping the barrel only. After insertion of the needle, the plunger can be moved slightly outwardly in the barrel thus to effect a slight vacuum effect, produce aspiration whereby the correctness of insertion can be determined. If blood appears at the inner end of the needle, the insertion should be corrected until no blood appears incident to such operation. Then injection of the medicament is effected by applying pressure against the head 25 at the outer end of the plunger to move it inwardly. The pressure of the plunger stem 26 directly against the stopple 37 forces the ampoule inwardly and causes the needle point 18 to pierce the stopple 36 as shown in Fig. 3. Then continued inward movement of the plunger forces the stopple 37 inwardly and causes forced ejection of the medicament through the needle in the usual way. After injection has been completed, the needle is withdrawn and the unit may be discarded.

7 It is anticipated that the barrel and plunger shall be cast of plastic or of any other suitable materials. Dimensions might be varied to meet requirements for any particular use.

The advantages of this particular construction over present day syringes of a like character are numerous and inherent in the details of construction. It is manufactured from a relatively inexpensive plastic material and may be produced mechanically by mass-production methods. The medicament containing ampoule is aseptically packed into the syringe at the factory thereby eliminating the possibility of unnecessary contamination or error by the administrator.

8 A further advantage resides in the double wall protection of the medicament whereby a dead air space is provided. This is best illustrated in Figure 2. The air space between the walls will give reasonable protection to the contents of the ampoule against temperature changes during storage.

9 Still a further important advantage of my syringe construction is the means whereby there may be repeated aspiration to determine if the needle is piercing a blood vessel. This may be accomplished without removing the needle from the patient, thus making additional punctures of the flesh unnecessary. The details of construction which makes this function possible have been previously described.

Having thus described my invention, what I claim as new therein and desire to secure by Letters Patent is:

1. A hypodermic syringe for the injection of a liquid from a cylindrical ampoule having a sealing stopple of a pierceable material fixed therein at one end and a stopple of piston form movably fitted in its opposite end portion; said syringe comprising a tubular barrel, open at one end to receive the ampoule thereinto and closed at its other end mounting a hypodermic needle within that end; said needle having a sharpened inner end portion extended into the barrel to an extent sufficient to be projected through the sealing

stopple of the ampoule when it is forced thereagainst, and a plunger comprising a tubular body telescopically fitted within the said barrel in an air tight joint and freely about an ampoule contained therein, and having a closing wall at its outer end and a stem extending from said closing wall, within the body to engage with the movable stopple of the contained ampoule as a means for moving the ampoule to cause its sealing stopple to be pierced by the sharpened inner end of the needle and then to advance the movable stopple within the ampoule to effect the ejection of the liquid therefrom through the needle.

2. A hypodermic syringe as recited in claim 1 wherein the inner end portion of the tubular body of the plunger has a flared flexible end portion that engages the barrel wall in a pressure retaining joint, thus to provide for the building up of air pressure about the contained ampoule by the inward movement of the plunger.

3. A hypodermic syringe as recited in claim 1 wherein the tubular body of the plunger fits at its open end within the said tubular barrel in an air tight joint, and provides clearance between its walls and the ampoule, thus to make possible the building up of air pressure about the ampoule incident to the advancement of the plunger into the barrel.

4. A hypodermic syringe as recited in claim 1 wherein the tubular body of the plunger fits within the said tubular barrel in an air tight joint, and provides clearance between its walls and the ampoule, thus to make possible the building up of air pressure about the ampoule incident to the advancement of the plunger into the barrel, and wherein the tubular body of the plunger has internal protuberances to frictionally engage the side walls of the ampoule when the plunger is applied to the barrel, to provide a holding contact whereby an outward movement of the ampoule with an outward aspirating movement of the plunger may be effected.

5. A hypodermic syringe as recited in claim 1 wherein the inner end portion of the tubular body of the plunger is flexible and slightly flared, and is beveled to a thin edge that engages closely and in air sealing contact with the barrel walls.

6. A hypodermic syringe as recited in claim 1 wherein the tubular body of the plunger fits telescopically in the barrel in an air tight joint, and wherein the said tubular body is formed longitudinally on its inner surface with inwardly projecting ribs to engage with and axially center the ampoule therein as the plunger receives the ampoule therein, and which ribs frictionally grip the ampoule for effecting its movement with an aspirating movement of the plunger.

7. A syringe as recited in claim 1 wherein the 60 barrel receives the ampoule therein with substan-

tial clearance, and wherein the barrel is formed within its needle containing end, with a diametrically constricted position to receive the end portion of the ampoule therein as a means of axially centering it relative to the barrel.

8. A syringe as recited in claim 1 wherein the barrel receives the ampoule therein with substantial clearance, and wherein the barrel is formed within its needle containing end, with a diametrically constricted position to receive the end portion of the ampoule therein as a means of axially centering it relative to the barrel, and wherein the tubular plunger body receives the ampoule telescopically thereinto with clearance between them as the plunger is advanced into the barrel, and said body is formed internally with longitudinal ribs to axially center the ampoule in the tubular body.

9. A hypodermic syringe for the injection of 20 liquid medication from a cylindrical ampoule that has a sealing stopple of soft rubber, or the like, fixed therein at one end, and a stopple of piston form movably fitted in its other end portion; said syringe comprising a tubular barrel, open at one 25 end and having an internal diameter sufficient to contain the ampoule therein with substantial clearance between them, and closed at its other end and mounting a needle coaxially thereof, formed with a sharpened inner end portion extended into the barrel, and a plunger comprising a tubular body, closed at its outer end and open at its inner end and telescopically received within the barrel in an air tight joint and to receive the ampoule therein with clearance, said barrel and 30 plunger when assembled providing a sealed air chamber about the ampoule in which pressure of the air is increased as the parts are telescoped together; said plunger having a stem fixed to its outer end wall and coaxially contained in the 35 body, to engage with the movable stopple of the contained ampoule to advance the ampoule to cause its sealing stopple to be pierced by the needle and then to move the piston stopple to eject the liquid through the needle; said barrel 40 having a diametrically constricted part adjacent the needle to receive and center the ampoule relative to the needle, and said body of the plunger having ribs on its inside walls to engage the ampoule as means for centering the ampoule and to 45 frictionally grip the ampoule for movement thereof with aspirating movement of the plunger.
